UNITED STATES PATENT OFFICE.

WILLIAM ALLEN PENFIELD, OF MERIDEN, CONNECTICUT, ASSIGNOR TO THE
BRADLEY & HUBBARD MFG. CO., OF SAME PLACE.

COMBINED WICK-STOP AND FLAME-EXTINGUISHER.

SPECIFICATION forming part of Letters Patent No. 678,126, dated July 9, 1901.

Application filed October 24, 1900. Serial No. 34,123. (No model.)

To all whom it may concern:

Be it known that I, WILLIAM ALLEN PENFIELD, of Meriden, in the county of New Haven and State of Connecticut, have invented a new Improvement in a Combined Wick-Stop and Flame-Extinguisher; and I do hereby declare the following, when taken in connection with the accompanying drawings and the letters of reference marked thereon, to be a full, clear, and exact description of the same, and which said drawings constitute part of this specification, and represent, in—

Figure 1, a view in vertical broken section of a lamp provided with my improvement; Fig. 2, a detached view of one form which my improved thimble-like flame-spreader may assume; Fig. 3, a view thereof in transverse section on the line *a b* of the preceding figure; Fig. 4, a detached perspective view of the annulus or ring.

My invention relates to an improvement in lamp-burners, and more particularly to combined wick-stops and flame-extinguishers for thimble-like spreaders of lamps of the central-draft or Argand type, the object being to produce at a low cost for manufacture a reliable and effective device of extreme simplicity of construction.

With these ends in view my invention consists in a stationary thimble - like flame-spreader encircled by a loose vertically-movable ring, the vertical movement of which is limited by the engagement of its inner edge with detents or stops located upon the outer surface of the spreader.

My invention further consists in certain details of construction and combinations of parts, as will be hereinafter described, and pointed out in the claims.

In carrying out my invention I employ, as herein shown, a combined wick - stop and flame-extinguisher in the form of a flat sheet-metal annulus or washer-like ring 2, the inner diameter of which is sufficiently greater than the external diameter of that portion of the thimble-like flame-spreader 3 which it encircles to permit it to have free vertical movement thereupon. The inner edge of the said ring is cut away to form several draft-spaces 3^a, which are separated from each other by short inwardly-extending stop-fingers 4, which

limit the upward and downward movement of the ring on the flame-spreader 3 by their engagement with an annular bead 5 and an annular shoulder 6, located upon the outer 55 face of the said flame-spreader, from the body of which, as shown, they are struck up, though this is not essential, and they may be replaced by any stops or detents of any other form or construction placed upon the exterior surface of the body of the spreader in right position for limiting the vertical movement of the loose ring. As shown, the flame-spreader is provided near its upper end with a deflecting-ring 7, while its top is formed 60 with a central opening for the upward passage through it of a binding-rod 9, the upper end of which is threaded for the reception of a thumb-nut 10, which is screwed down to a bearing upon the top of the spreader, which 65 is thus firmly secured in place and made stationary as to upward or downward movement. The lower end of the binding-rod is mounted in a spider 11, located within the inner wick-tube 12 of the lamp, the outer 70 wick-tube 13 of which forms a part of the lamp-burner, which may be of any approved construction. The space between the said inner and outer tubes receives the tubular wick 15, which is raised and lowered in any 75 desired manner. When the lamp is wicked, the upper end of the wick stands directly under the ring 2, which when the wick is raised will be lifted thereby until the fingers 4 of the ring engage with the bead 5, when the 80 ring will be stopped and the further lifting of the wick prevented. It is designed that the parts shall be proportioned so that the lifting of the wick will be stopped before the wick can be lifted high enough to cause the 85 lamp to smoke. When, on the other hand, the wick is turned down either by a slow or a so-called "plunging" movement, the ring 2 will drop by the action of gravity and so cut off the access of air to the upper end of 90 the wick that the flame will be extinguished.

It will be apparent that the particular construction of the thimble-like flame-spreader and the particular construction of the burner and lamp may be widely varied from the 100 form herein shown, it being only necessary, so far as my present invention is concerned,

to employ a thimble-like flame-spreader of a construction adapted to be secured in a stationary position and for the reception of a loose vertically-movable annulus or ring, portions of the inner edge of which are designed to be engaged with stops of some sort upon the exterior surface of the cone.

I would therefore have it understood that I do not limit the invention to the precise construction herein shown and described, but hold myself at liberty to make such changes and alterations as fairly fall within the spirit and scope of my invention.

Having fully described my invention, what I claim as new, and desire to secure by Letters Patent, is—

1. A thimble-like flame-spreader encircled by a loose, vertically-movable ring, the vertical movement of which is limited by the engagement of its inner edge with stops located upon the outer surface of the spreader.

2. A thimble-like flame-spreader encircled by a loose vertically-movable ring, the vertical movement of which is limited by stop-fingers formed in its inner edge to engage with stops located upon the exterior surface of the spreader.

3. A thimble-like flame-spreader encircled by a loose vertically-movable ring having its inner edge shaped to form draft-spaces and one or more stop-fingers, and limited in its

vertical movement upon the spreader by the engagement of its said finger or fingers with stops located upon the exterior surface of the body of the spreader.

35

4. The combination with a thimble-like flame-spreader, provided upon its outer surface with an annular bead and with an annular shoulder separated from each other, of a flat annulus or ring encircling the said spreader at a point between the said bead and shoulder, and free to move up and down between them.

5. In a central-draft lamp, the combination with the inner and outer tubes thereof, of a thimble-like flame-spreader set within the upper end of the inner tube, a binding-rod rigidly connected with the lamp and projecting upward through the said spreader, means applied to the projecting upper end of the rod for holding the spreader firmly in place, and a combined wick-stop and flame-extinguisher loosely movable, within predetermined limits, vertically upon the flame-spreader, and acting as a wick-stop and as a flame-extinguisher.

55

In testimony whereof I have signed this specification in the presence of two subscribing witnesses.

WILLIAM ALLEN PENFIELD.
